AUTOMOBILE ORNAMENT

Teddy R. Pope, Sr., Memphis, Tenn.

Application February 27, 1950, Serial No. 8,159

Term of patent 14 years

(Cl. D14—18)

To all whom it may concern:

Be it known that I, Teddy R. Pope, Sr., a citizen of the United States of America, residing at Memphis, in the county of Shelby and State of Tennessee, have invented a new, original, and ornamental Design for an Automobile Ornament, of which the following is a specification, reference being had to the accompanying drawings, forming a part hereof.

In the drawings:

Fig. 1 is a side elevational view of my new automobile ornament, the opposite side being substantially identical.

Fig. 2 is a top plan view of the ornament.

Fig. 3 is an inverted plan view of the ornament with the dotted lines of Figs. 1 and 2 omitted.

Fig. 4 is a front view of the ornament with all but minor portions of the dotted lines of Figs. 1 and 2 broken away; and

Fig. 5 is a rear view thereof with all but minor portions of the dotted lines of Figs. 1 and 2 broken away.

The characteristic features of my design reside in the portions shown by means of full lines in the drawing.

I claim:

The ornamental design for an automobile ornament, substantially as shown and described.

TEDDY R. POPE, SR.
